UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

FLEXIBLE DIAPHRAGM FOR THERMIC SIPHONS.

Application filed May 13, 1922. Serial No. 560,667.

To all whom it may concern:

Be it known that I, CHARLES GILBERT HAWLEY, a citizen of the United States, and a resident of Chicago, Cook County, Illinois, have invented a certain new, useful, and Improved Flexible Diaphragm for Thermic Siphons, of which the following is a specification.

My invention relates to improvements in so-called siphoned fireboxes, to wit, locomotive boiler fireboxes which contain Nicholson thermic siphons and the like. Such devices comprise water walls which depend from the crown sheet of the firebox and present intake necks that open through the side throat sheet of the firebox. As the device occupies the firebox and is subjected to the intense heat therein and the great variations of temperature which occur at different rates of firing, considerable differences of expansion and contraction are set up between the siphon or siphons and the firebox containing the same. Further, the siphon presents a more extensive surface to the crown sheet than to the throat sheet of the firebox, and as a result most of the expansion and contraction is, so to speak, localized in the region of the juncture between the neck of the siphon and the throat of the firebox. I find that the expansion stresses culminate upon a common line which passes through the forward end of the siphon neck and through the middle of the siphon top; in other words, a line which forms a rather acute angle with the flue sheet of the firebox. This is another way of saying that the expansion movements of the siphon within the firebox are neither wholly vertical nor wholly horizontal, but take effect upon a diagonal line so that there is a distinct downward thrust of the siphon neck upon the flue sheet or throat sheet containing the same as well as a fore-and-aft movement.

The object of my invention is to form the flue sheet in such manner that it may receive the neck of the siphon and freely respond to the movements thereof without danger of cracking any of the parts or breaking the autogenous welds by which they are united. It is extremely desirable that this joint between the firebox and the siphon shall be of a dependable nature and long life.

My invention will be readily understood

on reference to the accompanying drawings, which form part of this specification and in which Fig. 1 is a vertical cross section of a locomotive firebox embodying my invention; Fig. 2 is a vertical longitudinal section thereof; Fig. 3 is an enlarged sectional detail of the throat portion of the firebox and the end or neck of the siphon; Fig. 4 is an inside face view of the throat sheet taken from Fig. 3; Figs. 5, 6, 7 and 8 depict various sectional forms of the novel diaphragm formation which I employ herein; Figs. 9, 10, 11, 12 and 13 are detailed views illustrating modifications of the invention; Fig. 14 is a face view of a horizontally corrugated diaphragm plate containing a round hole to receive the siphon neck; Fig. 15 is a like view, but showing an oval hole for the siphon neck.

In Figs. 1 and 2 I have shown a locomotive boiler and its firebox 2 equipped with two Nicholson thermic siphons 3. The necks 3' of these siphons as shown pass through and are welded in the front or throat sheet 4 of the firebox. Thus the neck of the siphon is placed in communication with the front water space of the boiler. As understood, the top of each siphon opens directly into the upper water and steam space 6 of the boiler. My invention is concerned with the formation of the throat sheet 4. As a rule, in applying the siphon I first remove a section or patch of the original throat sheet and in place of the removed portion substitute a thinner plate or patch 7. The margins of this patch are welded to the original throat sheet along the line 8. The plate 7 is horizontally corrugated and may be formed in either rolls or press dies. In vertical section it may partake of any of the cross-sectional appearance represented in Figs. 5, 6, 7 and 8. My preference is for the very shallow corrugations of Figs. 5, 6 and 7; shown also in Figs. 3 and 4. The necks of the siphons pass through holes 9, provided therefor in the diaphragm plate 7 and are secured by autogenous welds 10, see Fig. 3. By preference the corrugated plate is slightly flattened around each neck as shown at 11 in Fig. 4. The whole throat sheet is stayed or held by a large number of closely spaced stay-bolts 12. In spacing these I make no distinction between the corrugated plate and the remainder of the throat sheet or flue sheet, except that by preference the stay-

bolts which are headed in the corrugated diaphragm portion are of the well-known flexible type. It will be obvious that such a corrugated plate serves admirably to absorb all differences of expansion and contraction between the siphon and the remainder of the firebox, including both horizontal and vertical tendencies to movement.

While the simply corrugated portions or plates above described, and which, if desired, may be formed directly in the original throat sheet, are deemed the best, I nevertheless desire that it be understood that my invention comprehends other forms of corrugated diaphragm sections or plates. To this end I have depicted several such additional forms in Figs. 9 to 13. Figs. 9, 10 and 11 illustrate plates having two large corrugations, the lower larger than the upper. Figs. 12 and 20 illustrate corrugated plates which are dis-

tinguished by flanged openings 13 for the reception of the end of the siphon neck.

This invention is of very simple nature, but of very clearly defined and well recognized importance.

Having thus described my invention, I claim as new and desire to secure by Letters Patent:

The herein described siphon diaphragm comprising a horizontally corrugated metal sheet of firebox material containing an opening for a siphon neck, said horizontal corrugations terminating in spaced relation to the margin of said opening, thereby providing a plain uncorrugated zone surrounding said opening.

In testimony whereof, I have hereunto set my hand this 6th day of May, 1922.

CHARLES GILBERT HAWLEY.
